UNITED STATES PATENT OFFICE.

EDWIN E. SLICK, OF PITTSBURG, PENNSYLVANIA.

METHOD OF ROLLING INTERLOCKING SHEET-PILEING.

No. 852,984.

Specification of Letters Patent.

Patented May 7, 1907.

Application filed February 4, 1905. Serial No. 244,125.

To all whom it may concern:

Be it known that I, EDWIN E. SLICK, of Pittsburgh, Allegheny county, Pennsylvania, have invented a new and useful Method of 5 Rolling Interlocking Sheet-Piling, of which the following is a full, clear, and exact description, reference being had to the accompanying drawings, forming part of this specification, in which—

10 Figure 1 is a front elevation showing the roughing roll passes; and Fig. 2 is a similar view showing the succeeding passes, arranged for carrying out my improved process.

15 My invention relates to the rolling of irregular shapes suitable for interlocking with each other to form sheet piling.

20 The object of the invention is to provide a new and improved method whereby one or more broad flanges may be formed at one or both ends of the shape, and such flange or flanges bent into such form that the shapes will interlock with each other. In order to properly interlock in this manner the flange or flanges should be bent into a hook form.

25 My invention is designed to produce this result and provide a wide flange or flanges which are bent around so as to interlock with the next adjacent shape.

30 In the drawings, I show in Fig. 1 a three-high set of rolls 2, 3 and 4, containing five passes, marked respectively *a*, *b*, *c*, *d* and *e*. I introduce into the pass *a* a billet or bloom, 35 preferably of square cross-section. In the five roughing passes shown in this figure, the bloom is rolled with its central plane at an angle to the axes of the rolls. This is for the purpose of widening the flanges to the degree which is necessary or desirable where they are to be bent to inclose and interlock

40 with a portion of the next shape. In order to obtain this result I have found that it is not only important to roll the shape on an angle, but also to bend the flanges to an outward or obtuse angle relative to the web, this 45 angle being greater than 90 degrees. Thus, it will be noted that in passes *b*, *c*, *d* and *e* the flange portions 5 and 6 extend at obtuse angles to the web portion 7. In the succeeding passes the flanges are made thinner and

50 of greater width, while maintaining them at the obtuse angle to the web. The web is preferably always rolled at an angle to the axes of the rolls, though one or more passes might be interposed without this feature.

55 In Fig. 2 I show two sets of passes *f*, *g*, *h*, and *f'*, *g'*, *h'*, which are similar to each other.

The pass *g* or *g'* is on a different level from the other two passes in the same series, the rolls rotating constantly in the same direction in this case. The blank coming from the pass *e* is passed through one of the sets of three passes. The passes *g* and *g'* are the final reducing passes, in either of which the blank is brought to its final shape, having the wide flanges 5 and 6, the web 7, and the short 65 head flanges 8 and 9. In the final pass *h* or *h'* the flanges 5 and 6 are curved so as to extend past a plane through the center of the groove at right angles to the plane of the web. I thus form a shape in which the 70 curved flanges are partially inclosed and interlock with the head flanges 8 and 9 of the next shape, in accordance with the construction shown in Patent No. 639,884, granted to Samuel K. Behrend, on December 26, 75 1899.

It will be noted that in the successive reducing passes either wide flange after passing through a live groove is within a dead groove in the next pass; that is, in each pass, one 80 flange is within the live groove and the other within the dead groove, the flanges being reversed in this regard in the successive passes. By so alternating the position of the flanges each flange is widened while passing through 85 the live groove, the flanges widening alternately.

The advantages of my invention result first from the rolling of a flange or flanges of sufficient width so that they may be bent around 90 in such form as to interlock with the next shape; and second, from the bending of such flanges past the plane at right angles to the plane of the web, so as to bring them to a position where they will interlock with and hold 95 the flange of the next shape.

I have found in practice that the rolling of the shape at an angle and the bending of the flanges to an outward obtuse angle of more than 90 degrees to the web, are important 100 features in obtaining the desired width of flange, though the wide flanges may be rolled in other ways; and my broader claims are not limited to this method.

The shape may be rolled with only one wide flange at one or both edges instead of with two wide flanges at one edge as shown, said flange or flanges being bent to interlocking position; the rolling may be carried out in two high mills, or any other suitable type of rolling mill; and many other changes may be made in the form and shape of the section and 105 110 115

the method of rolling, without departing from my invention.

I claim:

1. The method of rolling interlocking shapes for sheet piling, consisting in feeding the metal through successive passes in an angular position relative to the roll axes, forming two flanges extending along one edge of the web at an angle to the web which is other than a right angle, and then bending at least one of said flanges into hook shape while feeding the metal through a rolling pass; substantially as described.

2. The method of rolling sheet piling, consisting in reducing metal to form a shape having a web with oppositely directed flanges at one edge, and then bending at least one of the flanges into hook form while feeding the metal through a rolling pass; substantially as described.

3. The method of rolling sheet piling consisting in reducing the metal to form a shape having a web with flanges at one end and then passing the blank between rolls and thereby simultaneously bending both flanges into hook form; substantially as described.

4. The method of rolling shapes for interlocking piling, consisting in reducing metal to a shape having a web with two wide flanges at one edge, and a head at the other edge, and then passing the blanks between rolls and thereby bending at least one of the wide flanges into hook form; substantially as described.

5. The method of rolling shapes for interlocking piling, consisting in reducing metal with the web portion at an angle to the axes of the rolls, and forming opposite flanges at one edge extending at an outwardly obtuse angle to the web, and then bending said flanges into hook form while feeding the metal through a rolling pass; substantially as described.

6. The method of rolling shapes for interlocking piling, consisting in rolling metal with a web at an angle to the roll axes, and opposite flanges along one edge extending at other than a right angle to the web, rolling the flanges alternately in live and dead grooves, and then passing the blanks between rolls and thereby bending the flanges into hook form; substantially as described.

7. The method of forming shapes for interlocking piling, consisting in rolling a shape with a web having a head at one edge and two wide flanges at the other edge, and then passing the blank between rolls and thereby bending the wide flanges into hook shape; substantially as described.

8. The method of forming shapes for interlocking piling consisting in rolling the metal with flanges, having a web extending at an angle to the axes of the rolls and then passing the blank between rolls and thereby simultaneously bending both flanges into hook shape; substantially as described.

9. The method of rolling shapes for sheet metal piling, consisting in forming a shape with a web and two flanges, and then passing the blank between rolls and thereby bending at least one of said flanges to form with the other flange an inclosure having a mouth narrower than the inclosure; substantially as described.

10. The method of rolling interlocking shapes for sheet piling, consisting in feeding the metal through successive passes in an angular position relative to the roll axes, forming a straight web having two flanges extending along one edge of the web at an angle to the web which is other than a right angle, and then bending at least one of said flanges into hook shape; substantially as described.

11. The method of rolling sheet piling, consisting in reducing metal to form a shape having a straight web with oppositely directed flanges at one edge, and then bending by rolls at least one of the flanges into hook form; substantially as described.

12. The method of rolling sheet piling, consisting in reducing metal to form a shape having a straight web with flanges at one edge, and then passing the blank between rolls and thereby bending said flanges toward each other into hook form by contact with said rolls; substantially as described.

13. The method of rolling shapes for interlocking piling, consisting in reducing metal to a shape having a straight web with two wide flanges at one edge, and a head at the other edge, and then bending by rolls at least one of the wide flanges into hook form; substantially as described.

14. The method of rolling shapes for interlocking piling, consisting in reducing metal with the straight web portion at an angle to the axes of the rolls, and opposite flanges at one edge extending at an outwardly obtuse angle to the web, and then bending said flanges into hook form by contact with said rolls; substantially as described.

In testimony whereof, I have hereunto set my hand.

EDWIN E. SLICK.
